UNITED STATES PATENT OFFICE.

ROBERT HENRY FOWLER AND THOMAS BENSTEAD, OF LEEDS, ENGLAND.

APPARATUS FOR STEAM CULTIVATION.

SPECIFICATION forming part of Letters Patent No. 608,514, dated August 2, 1898.

Application filed September 23, 1897. Serial No. 652,756. (No model.)

To all whom it may concern:

Be it known that we, ROBERT HENRY FOWLER and THOMAS BENSTEAD, engineers, citizens of England, residing at the Steam Plough Works, Leeds, in the county of York, England, have invented certain new and useful Improved Apparatus for Steam Cultivation, of which the following is a specification.

This invention relates to improvements in the construction of apparatus for steam cultivation described in the specification of United States Patents No. 463,502, of 1890, and No. 534,216, of 1893.

We will describe the said improvements with reference to the accompanying drawings, in which—

Figure 1 shows a part front elevation of a plow-frame, showing the improved arrangement for the adjustment of the cultivating-tools and their skids, as also for angling and controlling the rear wheels. Fig. 2 shows a part plan of these parts. Fig. 3 shows a sectional side view. Figs. 4 and 5 show side and front views of combined skimmers and colters. Fig. 6 shows a longitudinal section of the fore carriage with the improved caster mechanism, as also the adjustment of the framed arms carrying the cultivating-tools. Fig. 7 shows a plan. Fig. 8 shows a front view of the bracket adjustment for the said framed arms. Fig. 9 is a plan of the complete machine with our improvements applied thereto, the machine being shown in the act of turning. Fig. 10 is a longitudinal section taken through the center line of Fig. 9. Fig. 11 is a detached view of the pawl-catch I.

The present improvements relate more particularly to the construction of machine described in the specification of United States Patent No. 534,216, and for the clearer understanding thereof we will designate certain parts with the same letters of reference as those designating the corresponding parts in the said specification.

One part of the present invention relates to the adjustment of the cultivating-tools. Instead of the skids W, described in the said specification, being attached to the framed arms P, (see details, Figs. 1, 2, 3, 9, and 10 of

the accompanying drawings,) carrying the 50 cultivating-tools, they are carried on the bar Q, by which the tools are raised and lowered. This bar is for this purpose fitted with vertically-adjustable brackets 1, to which are attached by a swiveling connection 2 skids 55 W, serving the same purpose as those between the cultivating-tools in the former construction. By means of the swiveling connection the skids are enabled to adjust themselves to any direction according to the line 60 of draft.

The bar Q, with its skids W, is free to move vertically by means of slides 23, fixed thereto in vertical guides 3, carried by the main longitudinal frame A, so that the cultivating-tools are thereby enabled to adapt themselves 65 to the contour of the land that is being operated on.

To facilitate the adjustment of the framed arms P with a view to their working level in 70 different kinds of soil, each framed arm has its pivot-pin S' (see details, Figs. 6, 8, and 10) at the leading end made vertically adjustable in a slotted bracket 5. This bracket has a screw 6 at its under side by turning which in 75 one direction or the other the pivot-pin S', and consequently the framed arm P, is either allowed to drop or is raised up, and it is then secured in its adjusted position in the bracket 5 by the clamping-nut 4 on S'. 80

By arranging the skids W on the bar Q as described, instead of on the framed arms P, we are enabled to use skimmers and knife or revolving colters on the said arms, which are well-known adjuncts of horse and other 85 plows and which serve to prevent any of the top surface of the land remaining on the top after plowing and to prevent the plow from clogging up. According to our present improvement we arrange the skimmers 7 directly behind the colters 8, (see details, Figs. 4, 5, and 9,) the skimmers being adjustably attached to the colters by means of slotted holes and screw-bolts, as shown. Thus any 90 surface growth is at once caught up by the 95 skimmer 7 and turned into the furrow.

Another improvement relates to the arrangement of the fore-carriage caster mech-

anism. The fore carriage J, Figs. 6, 7, 9, and 10, has its front end formed with a ring 9, with a groove 10 of semicircular section. Within this ring is placed a second 5 ring or disk 11, having a peripheral groove 12 of semicircular section, which in meeting the groove 10 of ring 9 with a certain amount of play forms therewith a closed circular groove, into which is introduced a circum- 10 cle of bearing-balls 13, so that disk 11 constitutes a turn-table turning freely upon the ring of balls. The ring 9 is suitably formed in two halves fixed together for enabling the balls to be introduced. The disk 11 has a central downwardly-extending socket 14, in which is fitted the caster-bracket 15, so as to be vertically adjustable therein by means of the screw 16. Thus the caster is afforded the greatest possible freedom of rotation in 15 either direction on the ball-bearing in following the direction of the draft, and whatever such direction may be or whatever may be the movement of the fore carriage the weight and strains on the latter will be transmitted 20 in an equally-distributed manner over the full circle of balls.

Another improvement relates to the coupling-link E, connecting the lever D² of the rear wheels C with the screw-spindle E² in the said 25 Patent No. 534,216. According to our present improvement, as shown in detail at Figs. 1, 2, 3, 9, and 10 of the drawings, we construct the said link in two parts 17 18, of which the forked part 17 is pivoted to the nut 30 of the screw-spindle E², while the part 18 is pivoted to the lever D² on the pivot-joint of the axle of the rear wheel C. The parts 17 18 being united by a screw connection, it will be seen that by adjusting the length of the 35 40 link the position of the wheel C relatively to the frame A can be accurately adjusted.

Another improvement relates to the pawl- 45 catch I, described in the said Patent No. 534,216, which engages with the toothed ratchet on the wheel C for preventing backward rotation. At certain times, especially when the plow is being turned (either uphill or downhill) on sloping land, it is desirable that the wheel C should have a certain amount 50 of freedom to run back before such motion of the wheel is stopped. For enabling this to be done we construct the said pawl in two parts, as shown at Figs. 3, 10, and 11 of the drawings. The one part 19 consists of a catch- 55 block which engages with the teeth of the ratchet-wheel 20 on the wheel C and is adapted to slide within adjustable limits upon the stem 21, forming the other part, which is pivoted to the framing. This stem may for 60 this purpose have a series of holes in its lower part, as shown, into one or other of which a pin is inserted, according to the amount of play required, or it may have any equivalent arrangement of adjustable stop, 65 and it has a projection or shoulder on its up-

per part. The catch-block 19 is allowed to slide down on the stem until it is stopped by the said pin or, as shown in dotted lines at Fig. 11, by a collar at the end of the stem. During the turning motion of the plow the 70 wheel C requires to be locked; but before this is effected a certain freedom is given, as it will be seen that the ratchet-wheel 20 is free to turn in the backward direction, as shown by the arrow, Fig. 11, taking with it 75 the block 19, which will slide upward on stem 21 until the block abuts against the shoulder at 22 on the stem, as shown by the full lines, Fig. 11, when it will arrest the further backward rotation of the wheel. By this means 80 the pawl-catch can be set at will to allow the pivoting-wheel C in turning to run back the distance found most suitable.

If when the block 19 is in the raised position a pin be inserted in the hole immedi- 85 ately under it, it will operate as an ordinary pawl, preventing any backward motion.

Having thus described the nature of this invention and the best means we know of carrying the same into practical effect, we 90 claim—

1. In apparatus for steam cultivation, the combination of a vertically-movable bar Q carrying the framed arms P of the cultivating-tools, slides 23 fixed to bar Q and working in vertical guides 3 carried by the main frame A and skids W swiveling on standards 95 1 adjustably secured to bar Q, substantially as described.

2. In apparatus for steam cultivation, the 100 combination of framed arms P carrying the cultivating-tools, colters 8 fixed on said arms P and having skimmers 7 adjustably attached thereto, a bar Q on which the framed arms are pivotally mounted, slides 23 fixed to said 105 bar Q and working in vertical guides 3 on the main frame A, and slotted brackets 5 fixed to the framing in which the pivot-pins S' of the arms P are vertically adjustable by means of screws 6, substantially as described. 110

3. In apparatus for steam cultivation such as is herein referred to a caster for the fore carriage consisting of a caster-wheel and bracket combined with a ring or disk 11 with peripheral groove, mounted within a grooved 115 ring 9 on the fore carriage and supported by balls 13 running in the grooves of the rings 9 and 11, substantially as described.

4. In apparatus for steam cultivation such as is herein referred to, the combination with 120 the lever D² on the pivot of the axle of the rear wheel C of a divided link 17, 18, adjustable in length, connecting the said lever to the nut on the screw-spindle E² substantially as and for the purpose set forth. 125

5. In apparatus for steam cultivation such as is herein referred to, a pawl-catch for preventing the backward rotation of the wheel C constructed of two parts, of which the block 19 that engages with the ratchet-wheel of the 130

wheel C is free to slide within adjustable limits upon the second part or stem 21 pivoted to the framing, for the purpose of permitting a certain amount of backward motion to the wheel C before it is locked, substantially as described.

5 In testimony whereof we have signed our names to this specification, in the presence of

two subscribing witnesses, this 2d day of September, A. D. 1897.
